(57) **CLAIM**

The ornamental design for a rear diffuser for an automotive vehicle, as shown and described.

DESCRIPTION

FIG. 1 is a front and left side perspective view of a rear diffuser for an automotive vehicle.

FIG. 2 is a front view of the rear diffuser of FIG. 1.

FIG. 3 is a rear view of the rear diffuser of FIG. 1.

FIG. 4 is a right side view of the rear diffuser of FIG. 1;

FIG. 5 is a left side view of the rear diffuser of FIG. 1;

FIG. 6 is a bottom view of the rear diffuser of FIG. 1;

FIG. 7 is a top view of the rear diffuser of FIG. 1; and,
FIG. 8 is a front and left side perspective view of the rear diffuser of FIG. 1 showing the diffuser installed on a vehicle.
The dashed lines are for illustrative purposes only and form no part of the claimed design.
